UNITED STATES PATENT OFFICE.

FRANCIS C. W. STELTER, OF ASTORIA, NEW YORK.

DYEING MACHINE.

Application filed June 16, 1921. Serial No. 478,103.

To all whom it may concern:

Be it known that I, FRANCIS C. W. STELTER, a citizen of the United States, and residing at Astoria, Queens County, State 5 of New York, have invented certain new and useful Improvements in Dyeing Machines, of which the following is a specification.

The present invention relates to machines 10 for dyeing, washing and rinsing of fibrous and other materials, particularly outer garments, hosiery, hats and similar articles.

A well known type of machine for accomplishing these purposes comprises essentially 15 a tank having two parallel spaced elliptical walls in the trough between which the dye liquor is held, and which has a paddle wheel for moving the liquor longitudinally of the elliptical trough so that 20 it circulates in an endless stream. The garments to be colored are placed in the dye liquor, usually being contained in fixed baskets through which the liquor runs.

In the present invention the apparatus is 25 designed and constructed to permit the articles to be colored to freely float in the dye liquor and to move continually with the same as it circulates in the elliptical trough. It is advantageous to permit the articles to 30 freely float in the dye liquor to secure a thorough exposure of the fibers to the coloring matter but when the articles float in this manner care must be exercised to prevent their catching on the wall of the tank 35 or being caught by the rotating, stirring or paddle wheel, the blades of which extend downwardly into the liquor and, which if unguarded, frequently engage some floating article and lift it out of the tank, often 40 causing it to be torn or injured, when of delicate construction. In accordance with the present invention an apparatus is provided in which the advantages of having the work freely float in the dye liquor are 45 realized and in which the disadvantages of the unguarded paddle wheel are obviated. A specially constructed paddle wheel is provided in which the blades are guarded in such manner that, while their stirring action 50 is unimpeded, they are prevented from catching and injuring any articles contained in the dye liquor. One embodiment of the invention will be disclosed in the accompanying drawings and in the following description.

In the drawings:

Figure 1 is a perspective view of the apparatus; and

Figure 2 is a side elevation partly broken away to show the construction of the paddle 60 wheel.

The spaced parallel walls 10 and 11 of the tank are substantially elliptical and in the trough between these walls the dye liquor may be placed, the depth of the liquor being such as to submerge the largest articles for which the tank is designed, and such that the paddle wheel 12, which is located substantially at the mid point longitudinally of the tank, will have its lower 65 portion submerged so that when the wheel is rotated the liquid will be moved, and also the articles submerged therein, around the elliptical trough in an endless stream.

The paddle wheel 12 is supported upon a 70 shaft 13 and is adapted to be driven by means of a belt 14 upon the pulley 15, at the desired speed. The paddle wheel has six radially arranged blades of substantially 75 equal size and two parallel disks 16 and 17 are secured to the lateral edges of the radial blades, the disks being coaxial and of equal size and the outer ends of the radial blades terminating substantially along lines extending between the peripheries of the disks. 80

In the operation of the apparatus the wheel 12 is rotated at the requisite speed and the liquor moves in an endless stream in its elliptical channel, carrying the garments with it. The radial blades repeatedly 85 dipping into the liquor of course engage the articles floating therein but cannot lift them from the tank, the guard disks 16 and 17 effectively preventing the blades from catching any article so as to lift it. 90 The pumping or stirring action of the blades is not impeded by the guard members but this action goes on as though they were not present.

Having thus described the invention what 100 I claim as new and desire to secure by Letters Patent is:

1. In a dyeing machine, in combination, a tank comprising spaced parallel inner and outer walls of substantially elliptical form and adapted to hold between them a body of dye liquor containing articles to be dyed, and a paddle wheel for moving the dye liquor and articles floating or contained therein in a substantially elliptical path be- 105 110

tween the walls of the tank, said paddle wheel being substantially half submerged in the liquid and having a plurality of radial blades extending from the periphery to the axis of rotation and being provided with a guard to prevent the ends of the blades from catching and tearing the articles in the liquid.

2. In a dyeing machine, in combination, 10 a tank comprising spaced parallel inner and outer walls of substantially elliptical form and adapted to hold between them a body of dye liquor containing articles to be dyed, and a paddle wheel for moving the

dye liquor and articles floating or contained 15 therein in a substantially elliptical path between the walls of the tank, said paddle wheel being substantially half submerged in the liquid and comprising a plurality of radial blades extending from the periphery 20 to the axis of rotation and having a disc secured to each side thereof, the diameter of which is substantially equal to the diameter of the paddle wheel.

In testimony whereof I hereunto affix my 25 signature.

FRANCIS C. W. STELTER.
